SHIRT COLLAR RETAINER

Lowell S. Bunch, Cape Girardeau, Mo.

Application September 22, 1955, Serial No. 535,935

1 Claim. (Cl. 223—83)

This invention generally relates to a shirt collar retaining device specifically intended to prevent a starched and laundered shirt collar from becoming wrinkled while being carried in a bag.

Persons whose occupations require a considerable amount of travel as well as those taking occasional trips find that freshly laundered and starched shirt collars become crushed, wrinkled and generally unkempt looking when they have been packed into a suitcase or a similar type of traveling bag which is notoriously crammed full of articles. Accordingly, it is the primary object of the present invention to provide a device for positioning within a shirt collar to retain the shirt collar in unwrinkled and uncrushed condition, thereby permitting the person employing the present invention to have available shirts having neat and attractive appearing collars.

Another object of the present invention is to provide a shirt collar retaining device which is adjustable for various sizes of shirts and also is provided with tabs on the upper and lower edge thereof for engagement with the upper and lower edge of the shirt collar for retaining the shirt collar and the present invention in assembled relation.

A further object of the present invention is to provide a shirt collar retainer in accordance with the preceding objects which includes spring means urging the collar retainer outwardly into intimate contact with the inner surface of the shirt collar for retaining the shirt collar in unwrinkled condition.

Other objects of the present invention will reside in its simplicity of construction, ease of assembly, effectiveness, adaptation for its particular purposes, and its relatively inexpensive manufacturing costs.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a perspective view of the shirt collar retainer of the present invention;

Figure 2 is a perspective view of a modified form of shirt collar retainer employing spring means urging the retainer into contact with the inner surface of the collar;

Figure 3 is a perspective view of the collar retainer itself, illustrating the means of adjustment and the resilient means for urging the collar retainer outwardly; and

Figure 4 is a detailed sectional view taken substantially upon a plane passing along section line 4—4 of Figure 3 illustrating the details of the spring and its association with the collar retainer.

Referring now specifically to the drawings, the numeral 10 generally designates the shirt collar retainer of the present invention for positioning within a shirt collar 12 disposed on the upper end of a shirt 14.

The shirt collar retainer 10 includes an elongated strip of flexible resilient material designated by the numeral 16

2

wherein the strip of material 16 is provided with overlapping ends 18 which will normally be disposed at the rear of the collar 12. The upper edge of the strip of material 16 is provided with a pair of spaced tabs 20 for engagement over the upper edge of the collar 12, and the lower edge of the strip of material 16 is provided with a pair of tabs 22 along the side edges thereof together with a pair of adjacent tabs 24 adjacent the front thereof wherein the tabs 22 and 24 are disposed for inserting under the edge of the collar 12 and between the front and back of the shirt 14. The tabs 22 and 24 in conjunction with the tabs 20 are so arranged that they will engage opposite edges of the shirt collar 12, thereby retaining the shirt collar retainer 10 against and alongside the inner surface of the shirt collar 12 for assuring that the shirt collar 12 will be retained in extended position. The tabs 22, 24 and the tabs 20 may be bendable for proper association with various types of shirt collars.

As specifically illustrated in Figures 2 and 3, an elongated wire spring member 26 may be provided on the inner surface of the strip member 16 wherein the wire spring 26 has free ends inserted under loops 28 punched inwardly from the strip of material 16 and the center of the wire spring 26 is provided with a coiled portion 30 wherein the two side portions and the overlapping ends 18 of the strip member 16 are urged outwardly into frictional and expanding contact with the inner surface of the collar 12. Also, the strip of material 16 may be provided with a male portion of a snap fastener designated by the numeral 32 on one end thereof and a plurality of longitudinally spaced female portions 34 for engagement with the male portion 32 wherein the effective size of the strip of material 16 may be adjusted for various sizes of collars.

The device may be constructed of any suitable material, although it is preferably constructed of some type of plastic or other relatively inexpensive materials. Besides the snap fastener arrangement, other means may be provided for adjusting the effective length of the strip of material, such as a series of loops and projections, a series of slots and projections, and any other suitable inexpensive type of adjustable connecting means. If desired, additional tabs may be provided or some of those illustrated may be omitted, depending upon the particular type of shirt and depending upon the conditions to be encountered by the shirt collars in the traveling bag.

It will be seen that the shirt collar retainer 10 of the present invention provides a device which is easily assembled and relatively inexpensive wherein one of the devices may be provided in each shirt collar that is packed in a traveling bag or in any other suitable packing box whereby the shirt collar 12 will be retained in unwrinkled condition during transportation thereof so that it will arrive at its destination in a most attractive condition.

The foregoing is considered as illustrative only of the principles of the invention. Further, since numerous modifications and changes will readily occur to those skilled in the art, it is not desired to limit the invention to the exact construction and operation shown and described, and accordingly, all suitable modifications and equivalents may be resorted to, falling within the scope of the invention as claimed.

What is claimed as new is as follows:

A shirt collar retainer comprising an elongated strip of flexible resilient material adapted to be disposed within a shirt collar, tabs on the upper edge of the strip for engaging the upper edge of the collar, tabs on the lower edge of the strip for positioning under the collar, thereby retaining the strip alongside the inner surface of a collar, said strip having overlapping ends, and means adjustably securing the ends together for expanding the strip into engagement with the inner surface of the collar, said strip

member generally conforming to the shape of the collar, and spring means in contact with said strip for expanding the strip of material into engagement with the inner surface of the collar.
